US00D963441S

(12) **United States Design Patent** (10) Patent No.: **US D963,441 S**
 Lofley, Jr. (45) Date of Patent: ** Sep. 13, 2022

(54) **TOOL**(71) Applicant: **Robert G. Lofley, Jr.**, Ocala, FL (US)(72) Inventor: **Robert G. Lofley, Jr.**, Ocala, FL (US)(**) Term: **15 Years**(21) Appl. No.: **29/753,832**(22) Filed: **Oct. 2, 2020****Related U.S. Application Data**

(60) Continuation-in-part of application No. 29/708,229, filed on Oct. 4, 2019, now Pat. No. Des. 922,838, which is a continuation-in-part of application No. 29/568,893, filed on Jun. 22, 2016, now Pat. No. Des. 871,174, which is a division of application No. 29/477,269, filed on Dec. 20, 2013, now Pat. No. Des. 760,564, which is a continuation-in-part of application No. 29/439,382, filed on Dec. 10, 2012, now Pat. No. Des. 786,638, which is a continuation-in-part of application No. 29/414,965, filed on Mar. 6, 2012, now Pat. No. Des. 676,735, which is a continuation-in-part of application No. 29/373,451, filed on Apr. 11, 2011, now Pat. No. Des. 663,193.

(57) **CLAIM**

The ornamental design for a tool, as shown and described.

DESCRIPTION

FIG. 1 is a right front perspective view of my new design for a tool head;

FIG. 2 is a right rear perspective view of FIG. 1;

FIG. 3 is a right side view of FIG. 1;

FIG. 4 is a left side view of FIG. 1;

FIG. 5 is a top view of FIG. 1;

FIG. 6 is a bottom view of FIG. 1;

FIG. 7 is a front view FIG. 1; and,

FIG. 8 is a rear view of FIG. 1.

1 Claim, 3 Drawing Sheets(56)
